UNITED STATES PATENT OFFICE.

CARL E. METHUDY, OF ST. LOUIS, MISSOURI, ASSIGNOR TO METHUDY AUTOMATIC LIGHTER COMPANY, OF EAST ST. LOUIS, ILLINOIS, A CORPORATION OF ILLINOIS.

IGNITION DEVICE FOR GAS BURNERS.

Application filed January 23, 1928. Serial No. 248,582.

This invention relates to ignition devices for gas burners and an object is to provide improved means for locating and retaining the pilot light ignition unit in proper relationship to the gas burners.

Another object of the invention is to provide an improved pilot light unit possessing the advantageous features of construction for obtaining the beneficial results hereinafter outlined.

Other objects will appear from the following description, reference being made to the drawing in which

Fig. 1 is a plan view of an embodiment of the invention for igniting the burners of a gas stove wherein the pilot light device is a unit supported in proper relationship to the gas burners by features of the present invention.

Fig. 2 is a detailed sectional view showing the improved construction of the tube from the ignition device and its connection with the burner.

The burners 1 receive gas from pipes 2 which are supplied with gas from a manifold 3 equipped with valves 4. An oven burner 5 is also supplied with gas from the manifold 3 through a valve controlled pipe 6. The burners 1 have their gas outlets through their upper side walls, and the burner 5 has its gas outlet through its lower wall and in these respects are of usual and familiar construction.

The pilot light device is of novel and improved construction comprising a pilot light casing 7 from which a series of tubular arms 8 open for serving the burners 1. An arm 9 opening from said casing 7 receives one end of a tube 10 for serving the oven burner 5 and approximately diametrically opposite from the tube 9 the casing 7 is provided with a tubular arm 11. The lid or cover of the casing 7 is shown as provided with a series of vent openings 12 and with a relatively large opening 13 above the plane of the opening to the tube 9 from said casing 7.

I modify the usual construction of the burners 1 by providing an arm 14 on each of said burners and by providing a gas outlet 15 in the side wall of each burner opposite the open end of the adjacent tube 8 and essentially in the same vertical plane, so that a part of the gas issuing from the burner will enter said tube 8 and pass to the pilot light casing, with the result that the gas will be ig-

nited and a pressure wave created in the tube 8 containing the gas. For connection of the tubes 8 with the arms 14 I provide on each tube a downwardly extending lug 16 engageable in a hole 17 in the adjacent arm 14.

I modify the construction of the ends of the tubes 8 from previous arrangements by providing in the outer end of each of said tubes a flaring recess 18 opening into said tubes and functioning readily to trap the gas passing from the adjacent opening 15 and to obtain proper air mixture.

The gas is supplied to the pilot light casing 7 through a tube 19 opening into the manifold 3 and controlled by an appropriate valve 20. The pilot light unit device comprising the casing 7 and its united parts is readily detachable and with equal facility may be replaced without possibility of being misplaced, since it is necessary to engage the lugs 16 in the holes 17. Thus, the tubes 8 are held in proper relationship to the burners and the gas outlets 15 from the burners.

The construction and arrangement may be varied in equivalent particulars without departure from the nature and principle of the invention.

What I claim is:—

1. A device of the character described comprising a pilot light casing, and a tubular arm formed integral therewith for supporting one side of said casing and directing a combustion pressure wave.

2. A device of the character described comprising a pilot light casing, a tubular arm formed integral therewith for supporting one side of said casing and directing a combustion pressure wave, and means for attaching said arm to a gas burner.

3. A device of the character described comprising a pilot light casing, a number of tubular arms integral with said casing and opening into the same for supporting said casing, and means for holding said arms in connection with gas burners.

4. The combination with a series of gas burners, and arms having rigid connection with and extending from said burners, of a pilot light casing, and a series of tubular arms opening from said casing and supported on said first named arms.

5. The combination with a series of gas burners, of a flash pilot light casing, a tube having rigid connection with and extending

- from said casing toward one of said burners, and means for holding said tube in connection with said burner.
6. The combination with a series of gas burners, and arms extending from said burners, of a flash pilot light casing, and tubes having rigid connection with and extending from said casing and engaging said burners and thereby supporting said casing.
- 10 7. The combination with a series of gas burners having gas outlets through one wall thereof, and each having another gas outlet through a side wall, of a flash pilot light casing, tubular arms having rigid connection with and opening from said casing toward said last named outlets in the respective burn-
- ers, and means for supporting said tubes by said burners, respectively.
8. A flash pilot light unit, a casing, a series of tubular arms formed integrally with said casing and extending laterally therefrom, and means in connection with said arms for engaging gas burners. 20
9. A device of the character described comprising a casing, a number of tubular arms integral with said casing and opening laterally therefrom and having flaring openings at their outer ends, and means in connection with the outer ends of said arms for engaging gas burners. 25

CARL E. METHUDY.
